TOBACCO GUIDING MACHINE

Kurt Adolf Körber, Dresden-Oberloschwitz, Germany, assignor, by mesne assignments, to J. C. Muller N. V., Rotterdam, Netherlands

Application October 11, 1938, Serial No. 234,477
In Germany October 18, 1937

2 Claims. (Cl. 131—109)

This invention relates to tobacco guiding machines, in which generally a tobacco conduit, which is shallow, supplies its tobacco to a conveying means.

The object of the invention is to overcome the objections of shaking up and down, the said conduit or part thereof; to overcome certain defects in connection with the conveying of the tobacco, and to overcome certain disadvantageous features in connection with the cutting of the tobacco fed by the conveying means. In addition, the object is to provide an improved fleecing device.

For this purpose, the invention consists of an improved fleecing device, in which a pivoted wiper concentrically arranged with the spiked roller, moves to and fro at considerable speed, and in its preferred embodiment, the wiper acts as a wall to a tobacco spreader from which the spiked roller obtains its tobacco.

The invention consists further in providing an openable and pivoted wall for the conduit which conducts the tobacco from a spiked roller and wiper to the conveying means; said pivoted wall extending close to the conveying means, and beyond another wall of the conduit, whereby the to and fro movement of said wall permits the tobacco in the conduit to be aired, and to freely descend, and then be pressed before it is pushed by said wall out of the conduit, and beneath the said other wall of the conduit spaced from said conveying means, said forced-out tobacco being delivered to the conveying means, and conveyed from said conduit on the conveying means.

The various parts are so coordinated in action and relative speed, that from the beginning of the operation, the tobacco is treated so as to be free from lumps, which enables it to be uniformly distributed and shaped into a substantially equally dense mass, so that the various cut off portions are of assured density and efficient distribution.

The invention will be further described in connection with the various embodiments shown in the drawing, and will be, finally, claimed.

In the accompanying drawing:

Figure 1 is a longitudinal section, partly in elevation, of the improved machine embodying the invention;

Figure 2 is a diagrammatic side view to show the action of the knife,

Figure 3 is a section on line 3—3 of Figure 1.

Similar characters of reference indicate corresponding parts throughout the various views.

Referring to Figure 1, the tobacco T is contained in a tobacco spreader 1, in which a known

tobacco spike roller 2 is arranged which rotates in the direction of the arrow 2a there shown. The roller 2 takes along during its rotation, tobacco from the spreader 1, in a manner to form a tobacco fleece upon the roller 2. In accordance with this invention, excess fleece is removed from the roller 2 by take-off member 3, which forms the front boundary wall of the tobacco space of the tobacco spreader. This wall 3 for stroking off the tobacco from the roller 2, is supported by a double armed lever 4 which is in turn supported by the shaft 5 of the roller 2. The lower free end of the lever 4 is pivoted to a lever arm 6 which acts as a crank rod, and which is actuated by the crank disc 7, rotating on the shaft 1a. The free end of the arm 6 is pivoted at 6a to the crank disc 7 eccentrically on the center shaft 1a. Known mechanism to rotate the roller 2, are utilized to rotate the same, but these are not shown in the drawing, as being within the skill of a mechanician.

Measured in respect to the speed of rotation of the roller 2, the speed of tobacco removing wall 3 with its wiping edge is such that the edge moves with relatively high speed concentric to the roller 2. By this coaction and the relative speeds, a very fine smoothing of the tobacco takes place on the roller 2, without balling of the tobacco in the angle x formed by the wall 3 and roller 2, which has been found to take place when a roller instead of such a wall with impinging edge is used.

This action of the wall 3 devised to obtain a most efficient fleece on the roller 2, now is followed by the action of a spiked roller 8 upon the fleece on the roller 2. The roller 8 rotates in the direction of the arrow 8a and in a direction opposite to that of the roller 2. The roller 8 is rotated by means of known operating mechanism, connected like roller 2, and disc 7, to the main drive.

The tobacco leaving rollers 2 and 8, drops by gravity into a substantially vertical conduit 9, and after passing therethrough it falls upon the endless conveyor band 10, which moves in the direction of the arrow 10a, and guides the tobacco flow towards the knife 20.

The conduit 9 is made in accordance with the present invention, in the form of a structure which has a stationary front wall 15, extending substantially perpendicularly from the tobacco container in which the roller 8 is located, and the wall 15 has its lower extremity near to the belt 10, and separated therefrom about the height of the tobacco flow on the belt 10. To the stationary wall 15 are applied lateral walls extending

rearwardly from the front wall 15, so as to form the side walls of the conduit. Within the side walls and spaced from the front wall 15, is a rear wall 11, pivoted at 12 to the lowermost part of the wall of the tobacco spreader. The rear wall thus pivoted at 12 is swingably supported, and in order to swing it to and fro, the rear of the rear wall is provided with a bracket 11a, supporting a pin or shaft upon which one end of a crank arm 13 is pivoted. The other end of the arm 13 is eccentrically disposed to the crank disc 14, and pivoted at 13a thereto, the disc 14 being rotated on the shaft 14a. A chain 14b passes over the sprocket 14c on the shaft 14a, and over the sprocket 1b. By the to and fro movement of the arm 13, the rear wall 11 is swung to and from full line position to dotted line position and back. The lower end of the rear wall 11 extends to the upper conveying surface of the belt 10, so as to substantially contact therewith, and so that any tobacco on the upper surface of the belt is pushed along by the rear wall 11 forwardly and through the space between the lowermost edge of the wall 15 and the belt 10.

This improved conduit formed by the front wall 15 and swingable rear wall 11, has the advantage that with every rearward movement of the wall 11, an airing of the tobacco within the conduit takes place. By this, the descent of the tobacco is facilitated and made easy. Thereby, a slight accumulation of the tobacco takes place at the lower end of the conduit near the belt, and this is then compressed by the return swinging movement of rear wall 11, by pressing the enclosed tobacco against the front wall 15. At the same time, the relatively compressed tobacco which has descended to the belt during the rearward swinging movement of the rear wall 11, is pressed by the end of the rear wall 11, which protrudes beyond the lowermost end of the front wall 15, along the belt and in the forward direction of the arrow 10a, during the forward movement of the belt. The tobacco in this dense condition is then moved forward by the belt.

In front of the front end of the belt 10, which passes over rolls 16 and 17, there is arranged a table portion 18 in advance of the roll 16, which receives the tobacco flow from the upper surface of the belt. As the moving tobacco now encounters a stationary surface on the stationary table surface 18, the tobacco is made more dense. The tobacco fed by the belt pushes against this resisting tobacco on the table 18. This frictional resistance can be augmented by roughing the table surface as indicated by 19b. Preferably, the free forward end of the table 18 has adjacent thereto an angular member 19a, the free end of which, in turn, is shaped to act as a cutting edge 19a, to cooperate with a knife edge 20. The length of the knife edge 19 and knife 20 is equal to the width of the table 18. The knife 20 is a blade knife and is supported by an arm 21 at each of its ends, the arms 21 in turn being supported by a pivotal roller shaft 22 pivoted to the frame of the machine. The knife 20 thereby partakes of a circular movement, during which it contacts with the edge 19a, and cuts off the portion of the tobacco flow to the extent that it projects beyond the edge 19a.

In respect to the edge 19a of the table 18, there is a supporting roller 31 having a space between it and the edge 19a upon which roller the tobacco projecting beyond the edge 19a passes. This roller is fastened to a shaft 24 suitably supported, which is freely rotatable. When, however, the

knife in its orbit comes within the sphere of the cutting edge 19a of the table 18, and by this action has separated the cut off tobacco portion, the knife is carried along the supporting roller 31 concentrically thereto. In consequence, the tobacco portion so cut off resting on the supporting surface 31, after reaching a certain inclined position, is guided off from and by the supporting surface, and reaches the hopper 25. From this it passes out of the discharge opening 26 into the collecting container 27 which takes each tobacco portion and moves it along to the next point of manipulation. The knife 20 coacts with the edge 19a and preferably a knife edge 20a is fastened at one side to a vertically moving member 30, or it can form also the under end of this member. Furthermore, there is provided a roller 31 with a smooth surface, which rotates in the direction of the indicated arrow 31a, and forms the supporting surface for the tobacco pushed beyond the edge 19a.

The knife 20a is, with its supporting element 30, so governed, that it first partakes of a vertical movement and thereby separates the tobacco portion which has reached the supporting surface 31. In immediate action therewith, the knife makes a movement of such a kind that its cutting edge descending on the periphery of the roller, moves concentric with the roller 31, and thereby remains in contact with the roller surface. This movement takes place in the conveying direction of the tobacco layer, so that the knife 20a with the wall 30 serves as a wiper, and wipes the separated tobacco portion from the roller 31 towards the left, in the sense of Figure 2. At the end of the wiping movement, the knife finds itself with its carrier roller 30, in the position indicated in dotted lines. Now the knife goes upwardly and so far that it is removed from the path of the freshly arrived tobacco on the roller 31. Then the knife goes to the right, back to the cutting position and the cycle begins anew.

The mechanism for moving the knife 20 is shown in Figure 1 in dotted lines. Guide rails 61 and 62 guide a member 63 to which the knife support 21 is pivoted at 22. The member 63 has a lateral pin 64 engaged by a fork 65, which is moved to and fro by an arm 66 as indicated by the arrow 67, and moves the pivotal support to and fro as indicated by the arrow 70. Suitable means 45 are provided to bring about the to and fro movement of the arm 66. To the arm 21 is pivotally connected at 71 a depending link 72, which extends downwardly so as to connect by suitable linkage either with the arm 66 or with the shaft 43 in timed relationship. Thereby, the knife is moved as explained, and as shown by the arrows 74 down, 75 over the roller, 76 up, and 77 back to the initial position.

Actuating devices of known kind are shown in Figure 1. The shaft 14a supports a sprocket wheel 40 over which a chain 41 passes, which passes over a sprocket 42, on the main driving shaft 43, having a pulley wheel 44. The shaft 43 has a worm 45, engaging a gear 43a on a shaft 47 supported in bearings 48. On the shaft 47 is a gear 43a engaging the worm 45, and bevel gear 49 engaging a conical gear 50 on a vertical shaft 51 held by bearings 52. To the shaft 51 a bevel 53 engages a bevel 54 on a shaft 55 which carries the drive pulley 77 of the belt 10, which passes also over the end pulley 16. To give the knife 20 the movement as described, guide rails 61 and 62 are supported by the frame, and these guide a guide 63, upon which the shaft 22 is supported, which is moved to and fro as shown by the dou-

ble-headed arrow 70. On the guide device 63 is a pin 64, which is engaged by a fork 65 on an arm 66, which is moved by the guide 63 to and fro as shown by the double-headed arrow 67 whereby the knife 20 is moved from full line to dotted line position. On the arm 21, a pin 71 is supported upon which the member 72, is connected and this member 72 is moved up and down as shown by the double-headed arrow, by mechanism not shown, to control the height of movement of the knife.

Divisional applications Serial Numbers 319,989 and 319,990, have been filed by applicant on February 21, 1940.

It is obvious that various changes and modifications may be made in the details of construction and design of the above specifically described embodiments of this invention without departing from the spirit thereof, such changes and modifications being restricted only by the scope of the following claims.

What is claimed is:

1. A tobacco guiding device, comprising a conveyor, a tobacco spreader, a walled conduit disposed between the conveyor and spreader, one of the walls of the conduit being stationary and another movable in respect thereto, the movable wall being longer than the stationary wall, pivotal means for supporting the movable wall, and

means for moving the pivoted movable wall towards and from the stationary wall, for airing the tobacco in the conduit, enabling it to descend, pressing the fallen tobacco, and forcing it out of the conduit to the conveyor, the stationary wall being spaced from the conveyor, and the forced tobacco being moved through the space between the stationary wall and conveyor by the movement of the pivoted movable wall.

2. In a tobacco guiding machine, the combination of a tobacco spreader, a spiked roller for the spreader, a supporting member extending above the spiked roller, a wiper above the roller and pivotally supported in said member, a conduit below the roller for receiving tobacco from the wiper and roller, said conduit being formed by an openable and pivoted wall and another wall, said pivoted wall extending beyond the other wall of the conduit, a conveyor belt substantially in contact with said openable and pivoted wall to receive tobacco from the conduit, said tobacco being moved by the pivoted wall in the direction of movement of the conveyor, means for moving the wiper to and fro in respect to the roller, means for moving to and fro the openable and pivoted wall of the conduit, and common actuating means for the last two named means.

KURT ADOLF KÖRBER.
